By Church & Church

His Attorney

UNITED STATES PATENT OFFICE.

HENRY J. M. HOWARD, OF WASHINGTON, DISTRICT OF COLUMBIA.

PRESSURE-CONTROL MEANS.

Application filed April 22, 1921. Serial No. 463,467.

To all whom it may concern:

Be it known that I, HENRY J. M. HOWARD, a citizen of the United States, residing at Washington, in the District of Columbia, have invented certain new and useful Improvements in Pressure-Control Means; and I do hereby declare the following to be a full, clear, and exact description of the same, reference being had to the accompanying 10 drawings, forming part of this specification.

This invention relates to a device for use on fire extinguisher systems and has for its object the provision of means whereby a single size coupling may be used on each 15 floor of a high building which while preserving the use of the standard fire department hose connection at the prescribed pressure, usually 80 pounds, will permit the use of local fire hose reduced to a considerably 20 lower pressure, say 30 pounds.

In the fire extinguisher systems now in use it is necessary to supply some means for reducing the pressure to one that can be handled in case of fire. Certain of the 25 larger buildings in New York city have a standpipe pressure of over 300 pounds, but the fire department pressure is standardized in that city at 80 pounds. At the present time a reducing valve of considerable size 30 and rather awkward construction is required.

One of the principal objects of the present invention is to provide a relatively inexpensive substitute for this complicated reducing valve, while preserving all of the advantages inherent to its use and in such substitution retaining all the certainty of operation, but yet materially lowering the cost of the equipment and materially improving the sightliness of the piping.

In practically all buildings of fair size swinging hose racks are pivoted upon the vertical nipple extending directly downward from the usual two and one-half inch angle valve, and it is strongly desired that the reducing or control elements shall not alter this nipple either in size or location owing to the enormous number of these Howard racks now in use, single buildings 50 being equipped with as high as 230 of these swinging hose racks.

In the present invention an annular disk or control element is secured to the nipple on which is swung the hose rack, this disk 55 having an orifice of such size as to bring the

pressure down to the required 80 pounds. By providing a series of such disks, say twelve in number, it is possible to reduce standpipe pressure in a building from a maximum of say 200 pounds to 80 pounds 60 on each floor by using the different sized disks beginning with those of small orifice on the lower floors and gradually increasing the size of the hole in the disk until on the upper stories no disk would be required. 65 In this way the pressure on each floor may be kept within a reasonable degree of accuracy to the standard set by the fire department.

In the drawings,—

Figure 1 is a view of my device as it is usually installed.

Fig. 2 is a vertical cross section through the rack supporting nipple and local reducing coupling.

Figure 3 is a central sectional view through the two disks.

The angle valve 10 is directly connected to the fire extinguisher system and is provided with the usual "hex" 11 into which is 80 screwed the rack supporting nipple. In addition to the threads 15 at its upper end the nipple is provided with threads 16 at its lower extremity which threads correspond to the fire department standards.

Just above the threaded portions 16 of the nipple the latter is provided with an integral nut 17 by means of which the nipple is screwed into place in the angle valve. The bore of the nipple is unrestricted and is 90 of standard size but the nipple is internally threaded as at 18 to receive the control element 19 which is an annular threaded disk of solid brass and is one of a series of such disks, all having the same outside diameter, 95 but varying in diameter of the central orifice 20.

The appropriate disk, depending upon the standpipe pressure on the floor where the angle valve is located, is screwed into the 100 nipple and remains in place unless for some reason the standpipe pressure itself is altered, which is unusual. In a case of this kind, however, it is a simple matter to unscrew the non-corrodible brass disk and replace it with another of the same type but with an orifice such as to give the standard fire department 80 pound pressure with the altered stand pipe pressure on the floor. By means of this disk, the outlet pressure 110

at the bottom of the rack supporting nipple is always of correct strength for fire department needs.

The fire department pressure is entirely 5 too strong for local service as it is not possible for unskilled men, even though of great strength, to successfully handle a nozzle carrying as much as 80 pounds pressure. The employees of the building, however, can 10 readily handle a hose carrying thirty, and even more, pounds of pressure up to a maximum of about fifty pounds pressure. This pressure cannot be obtained by any regulation in the nozzle itself, since by the laws 15 of most large cities, cut-off nozzles are prohibited, nor is it safe to rely upon valve control and this is not permitted by the fire underwriters, although it would not be objected to by the fire department provided 20 that the pressure when the valve is on full would be 80 pounds.

A simple and high efficient means for securing the lower pressure in the local hose line is illustrated in Fig. 2 and consists of 25 a reducing coupling which includes a hose supporting member 23 to which is permanently but rotatably secured a swivel ring 24 having the usual outward extending circular lugs 25 and being threaded in its in- 30terior bore to receive the external threads 16 of the nipple. At its lower end the swivel member carries an inwardly extending flange 26 riding in a groove 27 in the supporting member 23 and held in place by an 35 outward directed flange 28 at the upper end of the latter, this swivel being of the usual construction.

The central orifice of the reducing coupling is of such diameter at its narrowest 40 portion as at 30 to receive the expansion ring (not shown) which wedges the hose 31 firmly against the corrugated surface 34 of the wall 35. The lower member of the reducing coupling is counterbored as at 36 to 45 a diameter slightly in excess of the bore of the nipple and of such depth as to receive snugly a perforated disk 37 which forms the control member of the local hose line. The disk 37 is one of a series of disks quite 50 similar in size and use with the disks 19, and like them is provided with a cylindrical central orifice 38, the latter being of such size as to cut the pressure in the local hose line to such figures as has been predetermined 55 as the standard local pressure and which should not exceed fifty pounds. The disk 37 is preferably smooth on its outer edge for ease in inserting it in the reducing coupling as there is no need of having this 60 screw into place as does the disk 19, since the rubber gasket 40 which fits in an annular recess 41 in the swivel ring firmly secures this disk in place, the inner diameter of the gasket 40 being less than the outer 65 diameter of the disk 37.

The operation of the device is as follows: The apparatus is normally in the position illustrated in Fig. 1 with the local hose 31 empty and in position on the hose rack with the nozzle 42 at the end of the rack. The 70 hose 31 is at all times firmly secured to the annular wall 35 of the reducing coupling and the latter is in firm, but readily detachable, engagement with the nipple. In case of fire, the valve 10 is opened and the nozzle and hose are pulled from the rack. Since there is no cut-off in the nozzle the pressure in this pipe can never exceed the pre-determined local pressure of thirty pounds or whatever has been set as a standard. When 80 the members of the fire department arrive it is merely necessary for them to remove the local hose line and to place their own standard two and one-half inch hose line on the threaded portion 16. The pressure 85 which in the local inch and a half hose was held at, say, thirty pounds, is now at the standard fire department pressure of 80 pounds, since in uncoupling the local hose line the disk 37 was removed leaving the 90 disk 19 operating alone.

What I claim is:

1. In a fire extinguisher system, a main water line, a plurality of valves secured to said line at different elevations, a pipe extending from each valve for attaching a local hose line, and means within each of said pipes for reducing the standpipe pressure behind each valve to a predetermined fire pressure. 100
2. In a fire extinguisher system, a main water line, a plurality of valves secured to said line at different elevations, a pipe extending from each valve for attaching a local hose line, and a perforated disk within each of said pipes for reducing the standpipe pressure behind each valve to a predetermined fire pressure. 105
3. In a fire extinguisher system, a main water line, a plurality of valves secured to said line at different elevations, a pipe extending from each valve for attaching a local hose line, and a perforated disk detachably secured within each of said pipes for reducing the standpipe pressure behind each 110 valve to a predetermined fire pressure. 115
4. In a fire extinguisher system, the combination with a valve and a swinging hose rack, of means secured to said valve and supporting said hose rack, and of means smaller in size than the internal diameter of the valve opening for reducing the pressure in the local fire hose line. 120
5. In combination, a nipple, means detachably secured to said nipple for reducing the pressure of water passing from said nipple, and a coupling surrounding said means and adapted to connect the local fire hose with said nipple. 125
6. In a fire extinguisher system, a verti- 130

cal main water line, a plurality of nipples of a single standard outer diameter each having a restricted opening therein, the size of said openings varying with the elevation of the nipple to give the same approximate fire pressure at each nipple, a local coupling for each nipple and a pressure reducing means, independent of said nipple, for restricting the water pressure in the local line below that of the fire pressure at the nipple.

7. In combination, a water conveying

member, a disk detachably secured to said member to reduce the pressure of water passing therethrough, a coupling member adapted to be secured to said water conveying member, and a disk detachably secured to said coupling to reduce the pressure of water passing through said coupling to a lower amount than that provided by said first mentioned disk.

15

HENRY J. M. HOWARD.
